PENCIL SHARPENER

Roman de Malditch, Montauk Point, N. Y.

Application March 10, 1944, Serial No. 525,828

8 Claims. (Cl. 120—93)

My invention relates to pencil sharpeners and has particular reference to portable or pocket type sharpeners.

My invention has for its object to provide a pencil sharpener which can be cheaply and easily manufactured, which can be conveniently carried in a pocket, and in which the knife holding parts can be made of metal, plastic or other suitable material.

Another object of my invention is to provide a pencil sharpener in which the knife can be easily and quickly replaced without necessity for employing any tools and without unscrewing any screws which could be lost.

My invention is more fully described by way of an example in the accompanying specification and drawing in which—

Fig. 1 is an enlarged sectional view of my pencil sharpener;

Fig. 2 is a top plan view of the same;

Fig. 3 is a sectional view taken on the line 3—3 of Fig. 2;

Fig. 4 is an elevational view of the same;

Fig. 5 is an elevational view of the base portion of the pencil sharpener with the cap portion removed;

Fig. 6 is a top plan view of the sharpener with the cap and knife removed;

Fig. 7 is a bottom plan view of the same.

My pencil sharpener consists of a base 1 which can be made of metal, plastic, or other suitable material, preferably of a cylindrical shape, having a cylindrical side portion and a substantially flat top portion 2. A conical opening 3 is provided in the base, the large end of the opening extending to the periphery at the side, the narrow end extending to the diametrically opposite point where it is in communication with the top through a rounded opening 5. A narrow slot 6 provides a communication between the conical opening and the upper side of the base. A recess 7 is formed in the upper side of the base for a knife 8, dowel pins 9 extending from the base for engaging corresponding holes in the knife. The knife is so shaped that its cutting edge 10 extends into the opening 3 through a slot 6.

The base is recessed at 12 for a cap 13. Spiral or thread grooves 14 are provided at the sides of the recess for corresponding projections 15 at the inner sides of the cap. A flange 16 at the top of the cap engages the top of the base when the cap is screwed tightly in its place. A flat portion 17 of the cap extends toward the central portion of the base, covering the knife 8 and holding the same securely in the operative position on the 55

base. The flat portion 17 is tapered at both sides as shown in Fig. 2 to provide for any inaccuracy in the adjustment of the cap on the base so that the flat portion will not extend over the edge of the knife if the cap is not turned far enough or if it is turned too far. For the same purpose an opening 20 is provided in the cap, registering with the large end of the opening 3 and is elongated at the sides as shown in Fig. 4.

The cap is preferably made of the same diameter as the base and is knurled at 21 in the same manner as the base is knurled at 22. For replacing the knife when it becomes dull, the cap is given a quarter of a turn to the left, bringing the projections 15 opposite the ends 23 of the spiral slots or grooves 14 thereby allowing the cap to be removed. The knife can be then lifted from the pins 9 and replaced, clamping the new knife in the operating position by the cap.

It is understood, of course, that ordinary threads may be used for joining the cap with the base, but the described connection is preferred since it lends itself more conveniently to casting or moulding process.

It is understood that my pencil sharpener may be modified without departing from the spirit of my invention as set forth in the appended claims.

I claim as my invention:

1. A pencil sharpener comprising a cylindrical base having a conical opening having its large end at the periphery of the base and extending toward a diametrically opposite point of the base, the base having a recess at the upper side; dowel pins in the recess; a knife removably supported in the recess and having holes registering with the pins, the cutting edge of the knife extending into the conical opening; a tubular cylindrical cap; and means to removably hold the cap on the base, the cap having a portion on top extending over the knife.

2. A pencil sharpener comprising a cylindrical base having a conical opening in its side, the large end of the opening extending to the outside, the narrow end extending to the diametrically opposite point near the top of the base, the cylindrical member having a recess in the upper side; a knife removably supported in the recess, the cutting edge of the blade extending into the conical opening; a cap for the base; and threaded connections between the cap and the base for holding the cap in position and for clamping the knife on the base.

3. A pencil sharpener comprising a cylindrical base having a conical opening with its large end at the periphery and extending toward the dia-

metrically opposite point near the top of the base, the base having a recess at the top; a knife removably supported in the recess, the upper side of the knife being parallel to the upper side of the base; a tubular cylindrical cap; and means to removably hold the cap on the base and to clamp the knife on the base by the cap, the periphery of the cap forming substantially a cylindrical continuation of the lower portion of the base.

4. A pencil sharpener comprising a base having a substantially flat top and a conical opening extending from one side of the base diametrically across the base, the top of the base having a slot in communication with the conical opening; a knife, the upper side of the top portion of the base having a recess for the knife; a cap for the base, the cap and the base having interconnecting spiral portions for tightening the cap on the base and for clamping the knife on the base by the cap.

5. A pencil sharpener comprising a body having a flat upper side and a conical opening at the side having its large end extending to the outside and its small end extending to the opposite point of the base near the top side, the base having a slot in the upper side extending into the conical opening; a knife removably supported on the base having its sharp edge extending into the conical opening; and a cap removably fitted on the base, the cap having a recess at the side for clearing the large opening.

6. A pencil sharpener comprising a body having a substantially flat top and a conical opening

having its large end at the side of the base and extending with the small opening to the opposite point on the base near its top; a knife removably supported in a recess in the upper portion of the base, the base having a slot at the top extending into the conical opening for the sharp edge of the knife; and a cap removably attached to the base for clamping the knife in its operating position.

10 7. A pencil sharpener comprising a base having a conical opening with its large end extending to the outside, the narrow end extending to the opposite side of the base near its top, the upper side of the base having a slot extending into the conical opening; a knife removably fitted in a corresponding recess in the upper side of the base; and a cap removably attached to the base and having an opening on top for exposing the cutting edge of the knife, the upper portion of the cap being arranged to engage the knife and to clamp the knife to the base.

25 8. A pencil sharpener comprising a base having a conical opening extending from one side of the base to the opposite point at the other side, the upper side of the base having a slot in communication with the conical opening; a knife removably supported on top of the base with the edge of the knife extending into the conical slot; a cap removably fitted over the base, the cap being 30 of substantially the same width as the base, the base having a recess for the cap; and means at the cap for clamping the knife in an operating position.
